INVENTOR
VINCENT BENDIX

Dr. W. McConkey
ATTORNEY

UNITED STATES PATENT OFFICE.

VINCENT BENDIX, OF CHICAGO, ILLINOIS, ASSIGNOR TO BENDIX BRAKE COMPANY, OF CHICAGO, ILLINOIS, A CORPORATION OF ILLINOIS.

BRAKE.

Application filed December 3, 1927. Serial No. 237,385.

This invention relates to brakes, and is illustrated as embodied in an internal expanding brake for an automobile. An object of the invention is to provide a simple and inexpensive brake which is very powerful.

One feature of the invention relates to forming the brake friction means of at least three shoes arranged generally end to end, with the end shoes overlapping and preferably jointed to the opposite ends of the central shoe, without throwing the stiffening webs of the end shoes off center. This may best be accomplished by displacing the stiffening web of the central shoe at one side of the central plane of the shoes, preferably by a distance substantially equal to the thickness of the web.

Another important feature has to do with centering the friction means, when the brake is released, by means acting on the central shoe directly and acting on the end shoes through their joints with the central shoe. This novel centering means may include a spring, which preferably also urges the shoe away from the drum toward its released position, and which is illustrated as attached to a wedge lever acting on the shoe.

The above and other objects and features of the invention, including various novel and desirable details of construction, will be apparent from the following description of the illustrative embodiment shown in the accompanying drawing, in which:

Figure 1 is a vertical section through the brake, just inside the head of the brake drum, and showing the brake shoes in side elevation;

Figure 2 is a partial section, radially through the central shoe on the line 2-2 of Figure 1, showing the engagement of the centering lever with the shoe;

Figure 3 is a partial section, on the line 3-3 of Figure 1, through the applying and anchoring means; and

Figure 4 is a partial section, on the line 4-4 of Figure 1, through one of the joints connecting the shoes.

The illustrated brake comprises a rotatable drum 10, at the open side of which is a sta-

tionary support such as a backing plate 12, and within which is arranged the friction means of the brake, shown as including three shoes 14, 16, and 18 arranged generally end to end. Preferably each shoe is formed by welding a flat web 20 to an arcuate outer rim 22 carrying the brake lining 24, thus giving the shoe a T-shaped cross-section (see Figure 2).

According to one feature of the invention, and as best appears in Figure 4, the stiffening webs of the end shoes 14 and 18 are substantially in the central plane of the brake shoe assembly, while the stiffening web of the central shoe is offset or displaced at one side of this plane, preferably by a distance substantially equal to the thickness of the web, and is overlapped by shoes 14 and 18 at its opposite ends. The overlapped ends of shoes 14 and 18 may be connected to the opposite ends of shoe 16 by floating joints, shown as including pivots 26 and 28. The above-described arrangement makes shoes 14 and 18 interchangeable in the same brake, and also in right and left brakes.

The brake is applied, against the resistance of return springs 30, by means such as a pair of floating cams 32 engaging pairs of rollers 34 mounted on opposite ends of pivot pins 36 extending crosswise through the ends of shoes 14 and 18. Cams 32 are extended to form radial operating portions connected by a pivot 38 to an arm fixed on a brake applying shaft 40 which extends through relatively large openings 42 in the cams 32.

Shaft 40 is journaled in two stampings or bearings 44 welded to fixed anchor plates 46 secured to the backing plate 12 by posts or studs 48. Studs 48 may, if desired, also serve for the attachment of the return springs 30. The anchor plates 46 are notched out, at their opposite ends, to receive the projecting ends of pivots 36.

When the drum 10 is rotating clockwise in Figure 1 at the time the brake is applied, the torque of all three shoes is transmitted to the anchor plates 46 through the pivot pin 36 of shoe 18; if the drum is turning counter-clockwise, the anchorage is through the pivot pin 36 of the shoe 14.

The above-described anchorage and applying means is more fully described, and is claimed in my prior application No. 159,806, filed January 8, 1927.

5 According to an important feature of the invention, the shoe 16 is centered directly, and shoes 14 and 18 are centered indirectly through joints 26 and 28, by means such as a spring 50, shown as fastened at one end on the

10 backing plate and connected at its other end to a wedge lever 52 fulcrumed on a pivot 54 carried by the backing plate. Lever 52 is preferably formed with a cam slot 56 embracing a pin 58. Pin 58 may be provided 15 with a roller 60, to minimize friction, if desired. It will be noted that spring 50 also urges shoe 16 away from the drum toward its released position.

20 While one illustrative embodiment has been described in detail, it is not my intention to limit the scope of the invention to that particular embodiment, or otherwise than by the terms of the appended claims.

25 I claim:

25 1. A brake comprising three shoes, the two end shoes having stiffening webs in the central plane of the shoes, and the central shoe having a stiffening web offset from said central plane by a distance substantially equal to the thickness of said web and overlapping the ends of said end shoes.

30 2. A brake comprising three shoes, the two end shoes having stiffening webs in the central plane of the shoes, and the central shoe having a stiffening web offset from said central plane by a distance substantially equal to the thickness of said web and overlapping the ends of said end shoes, in combination with means connecting the overlapped ends of the end shoes to the opposite ends of the central shoe.

35 3. A brake comprising at least three shoes arranged end to end with the end shoes connected by floating joints to opposite ends of the central shoe and anchoring alternatively on one or the other of the end shoes, in combination with a centering lever acting on the central shoe directly and acting through said 40 joints on the end shoes.

45 4. A brake comprising at least three floating shoes arranged end to end with the end shoes connected by floating joints to opposite ends of the central shoe and anchoring alternatively on one or the other of the end shoes, in combination with a yieldingly-operated centering lever acting on the central shoe directly and acting through said joints 50 on the end shoes.

50 5. A brake comprising, in combination, a drum, at least three shoes arranged end to end and engageable with the drum, floating joints connecting the end shoes to opposite ends of the central shoe, and a lever member 55 acting on the central shoe and urging it to-

ward a centered position with respect to the drum.

6. A brake comprising, in combination, a drum, at least three shoes arranged end to end and engageable with the drum, floating joints connecting the end shoes to opposite ends of the central shoe, and a spring-operated lever acting to center the central shoe when the brake is released.

7. A brake comprising, in combination, a drum, at least three shoes arranged end to end and engageable with the drum, floating joints connecting the end shoes to opposite ends of the central shoe, and a lever acting to center the central shoe when the brake is released.

In testimony whereof, I have hereunto signed my name.

VINCENT BENDIX.
